CLAIM

The ornamental design for a bumper for an unmanned aerial vehicle, as shown and described.

DESCRIPTION

FIG. 1 shows a perspective view showing left, front, and bottom sides of a bumper for an unmanned aerial vehicle showing our new design;

FIG. 2 shows a perspective view showing top, front, and left sides thereof;

FIG. 3 shows a front plan view, the rear plan view being a mirror image thereof;

FIG. 4 shows a left side elevation view, the right side elevation view being a mirror image thereof and therefore not shown;

FIG. 5 shows a top plan view thereof; and,

FIG. 6 shows a bottom plan view thereof.

The broken lines illustrate portions of the bumper for an unmanned aerial vehicle which form no part of the claimed design.
